COMBING MACHINE FOR TEXTILE FIBERS

Carlo Schleifer, Milan, Italy

Application July 11, 1950, Serial No. 173,127

Claims priority, application Italy July 22, 1949

4 Claims. (Cl. 19—116)

1

This invention relates to a rectilinear combing machine, particularly suitable for the curling of cotton or other short fibers, as distinct from combing machines of the Heilmann type for wool or other long fibers and having entirely different operative features.

An object of this invention is to provide a combing machine, in which the scissor arms carrying the nippers are mounted on a lever rocking about a stationary axis and are provided with means for alternately moving said nippers in front of the circular comb and with detaching rollers, respectively, along a path comprising two arcs of a circle having their centres on the axis of the circular comb and of the stationary pivot of said lever, respectively.

A further object of this invention is to provide a combing machine of the type referred to above, having stationary guide means, causing the closed nippers to follow a path coinciding with an arc of a circle having its centre on the axis of the circular comb over the full period during which said nippers are within the range of said circular comb, while in the period during which the nippers approach the detaching rolls, the former are drawn apart, the upper nipper following a path such as to be rapidly withdrawn from the lower nipper, which follows a path along an arc of a circle having its centre on the axis of the pivot of the rocking lever.

A further object of this invention is to provide in a combing machine of the type referred to above a spring between the lever and free end of the arm carrying the lower nipper to permit a slight adjustment of the path followed by said lower nipper over the period during which the nippers are closed and are situated within the range of the circular comb, this adjustment permitted by the spring being obtained by the action of the inner nipper on the lower one which therefore describes during the above indicated period an arc of a circle having its center on the axis of the circular comb.

A further object of this invention is to provide in a combing machine of the type referred to above a supporting plate fulcrumed on the axis of the circular comb and carrying the stationary pivot, of oscillation of the lever having pivoted thereto the scissor arms carrying the nippers. In this manner, a slight rotation of the plate serves for adjusting the spacing between the lower nipper and detaching roll, without, however, changing the width of oscillation of the nippers.

Further characteristics and advantages of this invention will be understood from the appended

2

specification referring to the accompanying drawing which shows diagrammatically by way of example an embodiment and a modification.

Figure 1 is a diagram of a first embodiment of the device in the closed position of the nippers;

Figure 2 is a similar diagram in the open position of the nippers;

Figure 3 shows a modification.

1 denotes the pivot of the rotating comb P, having mounted at one end a normally fixed plate 2, which may be adjusted by means of an eccentric 5 acting on a pivot 3 of the plate 2 by means of the lever 4.

The plate 2 is provided with a shaped guide 6 and a pivot 7 for articulation of a rocking lever 8 which is actuated at its opposite end attached by link 10 hinged at 9 to the lever 8 and at 11 to an operating arm rocking about a stationary pivot 13.

15 The rocking lever 8 further carries a pivot 14 for oscillation of two arms carrying the nippers, namely, an arm 15 carrying the top nipper 16 and at its opposite end a roller 17 rolling within the guide 6, and an arm 18 carrying the bottom nipper 19 and at its opposite end an extension 20 supporting one end of a coiled spring 21, the other end of which bears on a projection 22 on the rocking lever.

20 The arm 18 is provided with an extension 23 having screwed therein a bolt 24 abutting at its end a surface 25 on the rocking lever 8.

The movement of the operating lever 12 rocks through the link 10 the lever 8 about the stationary pivot 7. The two arms 15, 18 carrying nippers are thereby moved in the direction of the arrow 14a together with the pivot 14 of the rocking lever 8. The nippers remain closed over the first section of the stroke under the action of the spring 21 which pushes the bottom nipper against the top one till the end of the bolt 24, which has been suitably adjusted, abuts the surface 25. The nippers then begin to open.

25 The path followed by the ends of the nippers 16, 19 depends upon the shape of the guide 6. The path is in the form of an arc of a circle having its centre on the axis of the rotating comb P, as long as the nippers remain closed. As soon as the nippers open, the bottom nipper 19 performs an arc of a circle 19a having its centre on the axis of the pivot 7, for the arm 18 carrying the nipper remains fixedly connected with the rocking lever 8 under the action of the spring 21 which has pushed the bolt 24 against the check surface 25.

30 The guide 6 draws the top nipper away rapidly

from the rotating comb P and towards the detaching rollers S along a curvilinear path 16a.

By adjusting the position of the eccentric 5 it is possible to arrange the plate 2 in a position such as to bring the nippers to the correct distance from the detaching rollers S when they reach the end of their stroke, leaving the length of the stroke and form of the path unvaried.

In the modification shown in Fig. 3 the top nippers are guided by guiding the sliding extension 26 of the arm 15 between two rollers 27, 28 rotating about pivots 29, 30 carried by the plate 2. By suitably shaping the extension 26 it is possible to move the nippers 16, 19 along the above described paths.

What I claim is:

1. A combing machine comprising in combination with a circular comb and with detaching rollers, a lever adapted to be rocked about a stationary axis, two scissor-like arms pivotally connected with said lever, an upper nipper carried by one of said arms, a lower nipper carried by the other arm, means for guiding the arm carrying the upper nipper to cause the same to travel along a path coinciding with an arc of circle having its center on the axis of the circular comb for the period during which the nippers are closed within the range of the circular comb, a spring between said lever and the arm carrying the lower nipper for maintaining the nippers closed and an adjustable stop member carried by said arm and engaging said lever to permit the opening of the nippers, when the latter are drawn towards said detaching rollers, the lower nipper travelling upon opening along an arc of a circle 35 having its center on the axis of said lever, while

the upper nipper is quickly drawn away by the guide means from said lower nipper.

2. A combing machine according to claim 1, in which said guide means comprise a stationary cam and a roller adapted to engage said cam, said roller being mounted on the arm carrying the upper nipper.

3. A combing machine as claimed in claim 1, in which said guide means comprise a pair of guide rollers mounted on stationary pivots and a shaped extension of the arm carrying the upper nipper and adapted to engage said rollers.

4. A combing machine as claimed in claim 1 comprising in addition a plate carrying said lever to be rocked about a stationary axis and said means for guiding the arm carrying the upper nipper, said plate being pivoted to the axis of said circular comb, whereby a slight rotation of the plate effects adjustment of the spacing between the lower nipper and detaching rollers without varying the width of the movement of the nippers.
